UNITED STATES PATENT OFFICE.

TALBOT C. DEXTER, OF PEARL RIVER, NEW YORK.

PAPER-FEEDING MACHINE.

No. 829,854.

Specification of Letters Patent.

Patented Aug. 28, 1906.

Application filed January 19, 1906. Serial No. 296,893.

To all whom it may concern:

Be it known that I, TALBOT C. DEXTER, a citizen of the United States, and a resident of Pearl River, in the county of Rockland and State of New York, have invented certain new and useful Improvements in Paper-Feeding Machines, of which the following is a specification.

My present invention relates to improvements in paper-feeding machines of the sheet-combing type in which the pile of sheets is acted upon by combing-feeding devices which comb or feather out the top sheets of the pile to gradually separate the successive sheets near the top, so they may be drawn from the pile periodically and fed to any machine arranged to operate upon the individual sheets. My improved machine, in common with prior known machines in this class, includes two sheet-combing devices arranged to operate upon opposite sides of the central longitudinal line of the pile for feeding the successive sheets forwardly upon the pile, the combing devices being independently controlled by sheet-actuated tripping devices, so that the successive sheets are approximately squared and registered as they are fed forward.

My present invention relates to improved features of construction, particularly with reference to the mechanism for raising and lowering the sheet-combing devices and the sheet-actuated tripping devices which control the operation of the combing devices.

In order that my invention may be fully understood, I will first describe the same with reference to the accompanying drawings, and afterward point out the novelty more particularly in the annexed claims.

Figure 1 is a plan view of part of a paper-feeding machine embodying my invention. Fig. 2 is a vertical longitudinal sectional view of the same, the section being taken on the line 2 2 of Fig. 1. Fig. 3 is a front elevation of the parts of the machine shown in Fig. 1. Fig. 4 is a detail elevation, showing the arrangement of the power-transmitting gears from the cam-shaft to the driven shafts, hereinafter referred to. Fig. 5 is an enlarged detail transverse sectional view of part of the comber-controlling mechanism, looking from the front of the machine. Fig. 6 is a detail plan view illustrating the mounting of the comber. Fig. 7 is an enlarged vertical longitudinal sectional view of the machine, show-

ing the comber controlling and operating mechanism. Fig. 8 is a detail plan view of the sheet-actuated pendulum. Figs. 9, 10, 11, 12, and 13 are enlarged detail views of the sheet-controlled clutch mechanism which throws out of operation the combing device. Figs. 14 and 15 are, respectively, a detail vertical longitudinal sectional view and a detail plan view of the drop-roller mechanism which passes the successive separated sheets from the pile.

Sheet-combing feeding-machines of the type to which my present invention relates are, as stated above, provided with two sets of sheet-combing devices arranged to operate at opposite sides of the machine. In the accompanying drawings I have shown only one-half of the machine, including only one of these sheet-combing devices; but it will be understood that two combing devices of the same construction are employed, each being independently controlled by the sheet-actuated tripping mechanism in the manner well understood in this type of machine.

The framework of my improved machine may be of any suitable construction to properly support the working parts hereinafter referred to. In the drawings, 1 represents one of a pair of vertical side frames. These side frames are suitably braced to make them rigid by means of stay-rods 2 3 and other frame parts (not shown,) and within the frame is provided a suitable table or support for carrying a pile of sheets, (indicated by the reference-letter P.) At the front of the pile of sheets I provide a series of vertical guide rods or strips 4, having forwardly-bent upper ends to facilitate the combing operation upon the top sheets of the pile.

5 is a constantly-driven shaft bearing the lower feed-rollers 6, said shaft 5 being braced at intervals by the yoked bearing-brackets 7.

8 represents drop-rollers journaled in the bifurcated rock-arms 9, mounted upon the transverse rock-shaft 10. The rock-arms 9 are shaped to form sheet confining or guiding fingers, as shown. The rock-shaft 10 extends transversely of the machine directly above the constantly-running lower shaft 5, and is suitably braced between its ends by two or more bracket-arms 11, rigidly secured to the auxiliary longitudinal frame-pieces 12. The rock-shaft 10 has adjacent to one end a rock-arm 15, to the forward end of which is pivotally connected at 16 a vertically-ex-

tending pitman 17, formed with a longitudinal slot 18, through which extends the main cam-shaft 20. The shaft 20 carries a cam 19 for reciprocating the pitman 17, the pitman 17 carrying at its upper end an anti-friction roller 17^a, which runs in peripheral contact with the cam 19, whereby the series of drop-rollers 8 are periodically raised and lowered for the purpose explained.

21 and 22 are respectively the under feed-roller and drop-roller of a folding-machine to which the feeder is to pass the sheets.

The main cam-shaft 20 extends transversely of the machine and is suitably journaled in the main side frames 1 and the auxiliary longitudinal frame-pieces 12. This shaft 20 is provided with a driving-pulley 25, as shown, or it may be driven in any other suitable manner, said shaft being the shaft 15 from which all other parts of the machine are driven. The cam-shaft 20 carries a large gear 26, which meshes with a smaller gear 27, secured to a larger gear 28, journaled upon a stud 29, projecting from the side frame of the 20 machine. The gear 28 meshes with and drives a smaller gear 30, journaled upon a stud 31, projecting from the side frame of the machine, and this gear 30 in turn drives a smaller gear 32, keyed to the projecting end 25 of the comber driving-shaft 35, hereinafter referred to, and a smaller gear 33, keyed to the projecting end of the constantly-rotating feed-shaft 5, above referred to.

40 is one of a pair of combing-wheels. 35 Each of these combing-wheels is freely journaled at 41 upon a rock-arm 42, which is freely journaled upon a sleeve 50, which is journaled upon the shaft 35. This shaft 35 has keyed to it a gear 45, which meshes with 40 a gear 46, secured to the combing-wheel 40, by which the combing-wheel is constantly rotated.

Projecting from one face of the comber-supporting rock-arm 42 is an integral lug 43 in which is mounted an adjustable tappet-screw 44. Secured upon the sleeve 50, alongside of the rock-arm 42, is a rock-arm 51, which is provided with a finger 52, which projects beneath the tappet-screw 44 just referred to, and by its engagement therewith lifts the combing-wheel away from the pile. By adjusting the screw 44 the limits of rise and fall of the combing-wheel can be fixed. The rock-arm 51 is moved in one direction 55 for lifting the combing-wheel by a spring mechanism which is released by the sheet-actuated tripping device hereinafter explained. The rock-arm 51 is moved in the opposite direction to allow the combing-wheel to move by gravity into engagement with the pile of sheets by the action of a cam, as will now be explained. Sleeve 50 has at its end opposite to the rock-arm 51 another rock-arm 55, to which is pivotally connected 60 a pitman 56, formed with a yoke-shaped up-

per end, which straddles the shaft 20. The shaft 20 carries a peripheral cam 58, which engages the antifriction-roller 57, journaled upon the pitman 56, whereby the rock-arm 55, sleeve 50, and finger 52 are moved once in 70 each revolution of the shaft 20 to allow the combing-wheel to rest upon the pile. The rock-arm 51 projects forwardly from the sleeve 50, and has pivotally connected to its forward end a latch-bar 60, extending vertically and riding in a socket 61 formed in a bracket 62, extending laterally from one of the central auxiliary frames 12. This latch-bar 60 is formed with a notch 61^a on one edge with which engages a spring-pressed pawl 63, 80 journaled at 64 upon bracket 65, secured to the frame-piece 12. The purpose of the latch-bar 60 and pawl 63 is to retain the rock-arm 51 and the spring device connected thereto (presently to be referred to) in position to 85 allow the operation of the combing-wheel.

I will now proceed to describe the spring device and will afterward explain the mechanism for releasing the latch under the control of the sheets fed from the pile. A rod 70 90 is pivoted at 71 to the rock-arm 51 and projects therefrom vertically through a guide-pin 72, projecting from the frame-piece 12. Surrounding the rod 70 and confined between the rock-arm 51 and guide-pin 72 is an expansion-spring 75, which tends to throw down the arm 51 and move up the finger 52 for raising the comber away from the pile of sheets. This spring tendency is normally restrained by the engagement of the pawl 63 100 with the latch-bar 60. Turning now to the sheet-actuated tripping mechanism for controlling the operation of the combing devices, I will first refer to the clutch mechanism which trips the spring-controlling latch under the 105 action of the sheet-actuated tripper and will then explain the structure of the tripping device. Keyed to the shaft 35, alongside of the gear 45, is a smaller gear-wheel 80, which is in constant mesh with a larger and narrower 110 gear 81, which is keyed to the inner end of a short hollow shaft 82, which is freely journaled in a bracket-bearing 83, supported from one of the frame-pieces 12. The hollow shaft 82 is rotatably and longitudinally movable in 115 its bearing 83, the breadth of gear 80 being sufficient to maintain the mesh with gear 81 while the shaft 82 is shifted longitudinally in its bearing. 85 is one member of a cam-faced slip-clutch secured to the face of the 120 gear-wheel 81 and having formed in its working face a plurality of radial cam-faced recesses 86. The opposite member 87 of the slip-clutch is provided with a plurality of radial cam-faced ribs or lugs 88 and is secured to or formed integral with a short hollow shaft 89, which is freely journaled in a bracket-bearing 90 also supported from the auxiliary frame-piece 12. This short shaft-section 89 carries upon its outer end a ratchet- 125 130

wheel 91. Secured within the hollow shaft 82 is a tube 95, which projects from the hollow shaft 82 into the hollow shaft 89. This tube 89 is brazed or otherwise rigidly secured 5 in the threaded nut or thimble 96, which is screwed into a threaded counterbore or recess formed in the inner end of the hollow shaft 82. The end of the tube 95, which projects into the hollow shaft 89, is partly closed 10 by a ring or washer 97, secured in the end of the tube and having a central opening through it. A bolt 98, having a cylindrical head 99, is passed through the central opening of the ring or washer 97 and through an opening 99 15 in the ratchet-wheel 91 and supports an expansion-spring 100, which is confined between the washer 97 and the cylindrical head 99, the outer threaded end of the bolt being engaged by the nuts 101 and 102. The tension 20 of the spring 100 can be regulated by adjusting the nuts upon the bolt. It will be observed from this construction that the spring 100 tends to hold the two parts of the clutch 85 87 in engaged position, so that the ratchet-wheel 91 will be rotated from the gear 81 25 through the hollow shaft-sections 82 89.

An arm 63^a projects downwardly from the pivot of the pawl 63, across the line of the hollow shaft-section 82, so that any longitudinal 30 movement of the shaft-section 82 toward the arm 63^a will disengage the pawl 63 from the latch-rod 60 to release the spring-rod which raises the comber from the pile. This movement of the shaft-section 82 is effected by arresting the ratchet-wheel 91 by the action of 35 the sheet moving from the pile in the manner which will now be explained.

105 is a bracket-arm extending downwardly from the bracket-bearing 90, and 106 40 is a rock-arm journaled in the lower end of the bracket-arm 105.

107 is a bracket-arm extending up from the bracket-bearing 90, and 108 is a rock-arm keyed to a rock-shaft 109, journaled in 45 the bracket-arm 107. Extending up from a rock-shaft 109 is a rock-arm 110, carrying an antifriction-roller 111, which operates in peripheral contact with the controlling-cam 112, keyed to the cam-shaft 20. A link 113 50 is pivotally connected at its opposite ends with the rock-arms 106 and 108 for yoking said rock-arms, so they will move together under the action of cam 112. The rock-arm 106 is yoke-shaped, as shown in Fig. 8—that 55 is, the arm 106 has a laterally and rearwardly branching finger 106^a, forming with the main part of the arm a U-shaped yoke or fork. The ends of arm 106 and finger 106^a carry the inwardly-presented bearing-screws 60 114, upon which are journaled the pendulum-shaft 115, carrying the downwardly-projecting trip-fingers 115^a, which project across the path of the sheets to points a little below the periphery of the constantly-rotating lower 65 feed-rollers 6. This pendulum trip-lever 115

115^a has secured to it a rearwardly-projecting finger 116, to which is pivotally connected the lower end of a link 117, which is pivotally connected at its upper end 118 to a pawl 119, journaled at 120 upon the bracket-arm 121, 70 projecting from the bracket-bearing 90. The pawl 119 is supported in operative relation with the ratchet-wheel 91, so as to arrest the rotation of the ratchet-wheel and the short shaft-section 89, upon which it is 75 mounted, when the pawl is dropped into engagement with the ratchet-wheel. A short rod 122 projects rearwardly from the pawl 119 and carries a small adjustable weight 123, by the adjustment of which the pawl 119 and 80 connected pendulum 115 115^a can be balanced to a nicety, so as to support pawl 119 just free of the ratchet-wheel and afford the least possible work for the sheet of paper when it engages the pendulum trip-fingers 85 115^a. An arm 125 projects upwardly and forwardly from the heel of the pawl 119 in position to engage the antifriction-roller 126, journaled on the rock-arm 108, whereby the action of cam 112 upon rock-arm 110 will 90 cause the rock-arm 108 to disengage the pawl 119 from ratchet-wheel 91 simultaneously with the lifting of the pendulum-fingers from the path of the sheet.

Extending longitudinally of the machine 95 at each side is a rock-shaft 135, journaled in bracket-arms 136, extending down from the auxiliary frame-pieces 12. At the forward end of each of these rock-shafts is a rock-arm 137, carrying at its upper end an antifriction-roller 138, which operates in engagement with a face-cam 139, keyed to the cam-shaft 20. Each of the rock-shafts 135 carries a horizontal rock-arm 140, which is adjustable circumferentially and longitudinally of the 100 rock-shaft, a set-screw 140^b being provided to secure the rock-arm in the desired adjusted position upon the rock-shaft. Each rock-arm 140 is formed with a yoke-shaped inner end 140^a, through the arms of which pass the 110 threaded pin or bolt 141, upon which is pivotally supported a depending weight 150. The weight 150 is held against displacement on the threaded rod or bolt 141, so that the adjustment of the rod or bolt in the yoked 115 end of the rock-arm will shift the weight 150 longitudinally of the machine. To effect this adjustment, I provide the threaded rod or bolt 141 with threaded nuts 143. The lower end of the weight 150 is bifurcated at 120 151 to receive a metal block 152, which is mounted in the bifurcated end 151 of the weight by means of a cross-pin. This metal block 152 carries a rubber pad 153, which is adapted to engage the rear end of the second 125 sheet of the pile just back of the rear edge of the top sheet as the top sheet is being fed off. The following brief explanation will make clear the operation of my improved machine. It being understood that a machine em- 130

bodying my improvements is provided with two sets of sheet-combing mechanisms, each independently controlled by a sheet-actuated tripping mechanism, as described, the machine is started in operation with the combing-wheels resting upon the top of the pile of sheets, the combing-wheels being driven through the gears, as above explained, and the pendulum-fingers 115^a, resting in vertical position, being dropped periodically into the path of the sheets and the pawls 119 being supported thereby out of engagement with the ratchet-wheels, so that the ratchet-wheels will rotate freely through the clutch mechanism 85 87, driven by the gears 80 81. In this normal operative position of the machine the spring elevating mechanisms for the combers are held out of action by the engagement of pawls 63 with the latch-bars 60. The 20 combing-wheels will operate until the top sheet is moved forward sufficiently to actuate one of the pendulum-fingers 115^a, which action will drop one of the pawls 119 into engagement with a ratchet-wheel 91, arresting 25 said ratchet-wheel, and thereby causing the disengagement of clutch members 85 87, with the consequent longitudinal displacement of shaft-section 82. The movement of shaft-section 82 disengages the pawl 63 from the 30 latch-bar 60, which allows the spring 75 to act for raising the first combing-wheel from the pile. This action is immediately followed by the same operation on the other 35 combing-wheel as the edge of the sheet in front of such combing-wheel reaches registered position. Immediately following the arrest of the two combing-wheels the cams 112 come into play to raise pendulum-fingers 115^a out of the path of the sheets and disengage pawls 119 from ratchet-wheels 91, and then the drop-roller mechanism operates for feeding the sheet off from the pile. As the sheet is engaged by the drop-roller mechanism the tail-grips 150 153 engage the under sheet just back of the rear edge of the top sheet for holding the pile. As soon as the sheet has left the pile the cams 58 come into action for forcibly rocking the arms 51 to again compress the springs 75 and allow 45 the combing-wheels to drop back by gravity upon the pile, it being understood that immediately preceding this operation the cams 112 have released the ratchet-wheels 91 by elevating the pawls 119, so that the clutch-members 85 and 87 have again come into 50 clutching position and allowed the shaft-sections 82 to return to their normal position, whereby the paws 63 are again permitted to engage the latch-bars 60 for holding springs 60 75 in compressed position in readiness for another operation.

Having thus described my invention, the following is what I claim as new therein and desire to secure by Letters Patent:

65 1. In a paper-feeding machine, the combi-

nation of a sheet-support, a rotary shaft, a rotary sheet-moving device driven thereby and adapted to be moved into and out of engagement with the sheets to be fed, a rock-arm adapted to raise and lower the sheet-moving device, a spring device connected with said rock-arm and tending to move it in its raising direction, a cam mechanism also connected with the rock-arm and adapted to move it in its lowering direction, a 70 latching device adapted to retain the rock-arm in lowered position with the spring device under tension, and sheet-actuated means adapted to trip said latch to allow the spring device to operate. 80

2. In a paper-feeding machine, the combination of a sheet-support, a rotary sheet-moving device movable toward and away from the sheet-support, and means for operating the sheet-moving device, with a rock-arm adapted to engage and elevate the sheet-moving device, a spring mechanism tending to move said rock-arm in one direction, a cam mechanism adapted to periodically move the rock-arm in the opposite direction, 85 a latch-bar connected with the rock-arm, a pawl or dog controlling the latch-bar and normally retaining the rock-arm in one position with the spring mechanism under tension, and sheet-actuated means adapted to 90 trip said pawl or dog to allow the spring mechanism to operate. 95

3. The combination of a support for a pile of sheets, a rotary shaft, a rotary sheet-moving instrument driven from said shaft and adapted to engage the top of the pile of sheets, a rock-arm supporting the rotary sheet-moving instrument, a second rock-arm adapted to raise and lower the sheet-moving instrument, a cam mechanism suitably connected 100 with said second rock-arm, a spring device also connected with said second rock-arm, a latch-bar connected with said second rock-arm, a pawl adapted to engage said latch-bar, and sheet-actuated means adapted to trip 105 said pawl for releasing said spring device. 110

4. The combination of a sheet-support, with a sheet-moving instrument adapted to be moved into and out of engagement with a sheet, a spring device adapted to elevate the sheet-moving instrument, means for restraining the action of the spring device, a longitudinally-movable throw-out shaft adapted to release said restraining means, and sheet-controlled mechanism for effecting the longitudinal movement of the throw-out shaft. 115 120

5. The combination of a sheet-support, with a sheet-moving instrument adapted to be moved into and out of engagement with a sheet, a spring device adapted to elevate the sheet-moving instrument, means for restraining the action of the spring device, a longitudinally-movable throw-out shaft adapted to release said restraining means, sheet-controlled mechanism for effecting the longitudinal 125 movement of the throw-out shaft. 130

nal movement of the throw-out shaft, and cam mechanism adapted to reset the restraining means.

6. The combination of a sheet-support, 5 with a sheet-moving instrument, means for actuating said instrument, a spring device adapted to elevate the sheet-moving instrument, means for restraining the action of the spring device, a throw-out shaft movable longitudinally and about its axis and adapted by its longitudinal movement to release said restraining means, and sheet-controlled means, actuated by the movement of the throw-out shaft about its axis, for effecting the longitudinal movement of said shaft.

7. The combination of a support for a pile of sheets, with a sheet-moving instrument, a driving-shaft operating said sheet-moving instrument, spring mechanism for elevating the 20 sheet-moving instrument, a latching device normally restraining the action of the spring mechanism, a longitudinally-movable throw-out shaft driven from said driving-shaft and adapted to release the latching device, and 25 sheet-actuated means for effecting the longitudinal movement of the throw-out shaft.

8. The combination of a support for a pile of sheets, with a rotary sheet-moving instrument, movable toward and away from the 30 pile, a driving-shaft operating said sheet-moving instrument, spring mechanism for elevating the sheet-moving instrument, a latching device normally restraining the action of the spring mechanism, a longitudinally-movable throw-out shaft adapted to release the latching device, sheet-actuated means for effecting the longitudinal movement of the throw-out shaft, and a cam adapted to reset the spring mechanism and 35 40 lower the sheet-moving instrument.

9. The combination of a support for a pile of sheets, with a sheet-moving instrument, a driving-shaft operating said sheet-moving instrument, spring mechanism for elevating the 45 sheet-moving instrument, a latching-bar connected with the spring mechanism, a pawl arranged to engage the latching-bar and normally restrain the action of the spring mechanism, a longitudinally-movable throw-out 50 shaft adapted to engage and trip the pawl from the latching-bar, and sheet-actuated means for effecting the longitudinal movement of the throw-out shaft.

10. The combination of a support for a pile 55 of sheets, with a rotary sheet-moving instrument, a driving-shaft, gearing between said driving-shaft and the sheet-moving instrument, a longitudinally-movable throw-out shaft, spring mechanism for elevating the 60 sheet-moving instrument from the pile, mechanism normally restraining the action of the spring mechanism, and means controlled by the sheet for imparting longitudinal movement to said throw-out shaft, whereby the 65 restraining mechanism is released.

11. The combination of a sheet-support, a sheet-moving instrument, means for elevating the sheet-moving instrument, a shaft-section movable longitudinally and about its axis, means actuated by the longitudinal movement of said shaft-section for releasing the elevating means, a second shaft-section movable about its axis, slip-clutch members secured upon the respective shaft-sections, means acting on one of said shaft-sections for moving both shaft-sections about their axis, and sheet-controlled means acting upon the other shaft-section to arrest its movement about its axis. 70 75

12. The combination of a sheet-support, a sheet-moving instrument, means for elevating the sheet-moving instrument, a shaft-section movable longitudinally and about its axis, yielding means normally resisting the longitudinal movement of said shaft-section, 80 means actuated by the longitudinal movement of said shaft-section for releasing the elevating means, a second shaft-section movable about its axis, cam-faced slip-clutch members secured upon the respective shaft-sections, means acting on one of said shaft-sections for moving both shaft-sections about their axis, and sheet-controlled means acting upon the other shaft-section to arrest its movement about its axis. 85 90

13. The combination of a sheet-support, a sheet-moving instrument, means for elevating the sheet-moving instrument, a shaft-section movable longitudinally and about its axis, means actuated by the longitudinal movement of said shaft-section for releasing the elevating means, a second shaft-section movable about its axis, slip-clutch members secured upon the respective shaft-sections, a pawl-and-ratchet mechanism adapted to arrest the movement about its axis of one of said shaft-sections, and a sheet-actuated tripping device controlling said pawl. 95 100

14. The combination of a sheet-support, a sheet-moving instrument, means for elevating the sheet-moving instrument, a shaft-section movable longitudinally and about its axis, means actuated by the longitudinal movement of said shaft-section for releasing the elevating means, a second shaft-section 110 movable about its axis, slip-clutch members secured upon the respective shaft-sections, a toothed member moved by one of said shaft-sections, a pawl adapted to engage said toothed member to arrest the movement of 115 said shaft-section about its axis, and a sheet-actuated tripping device controlling said pawl. 120

15. The combination of a support for a pile of sheets, a sheet-moving instrument, means for elevating the sheet-moving instrument from the pile, a rotary longitudinally-movable shaft-section, means actuated by the longitudinal movement of said shaft-section for releasing the elevating means, a second ro- 125 130

5 tary shaft-section, slip-clutch members secured upon the respective rotary shaft-sections, means yieldingly connecting the shaft-sections, a ratchet-wheel upon one rotary
5 shaft-section, a pawl adapted to engage said ratchet-wheel, and a sheet-actuated tripping device controlling said pawl.

16. The combination of a support for a pile of sheets, with a driving-shaft, a rotary sheet-moving instrument driven from said shaft, means for elevating the sheet-moving instrument, a rotary longitudinally-movable shaft-section also driven from the driving-shaft, means actuated by the longitudinal movement of said shaft-section for releasing the elevating means, a second rotary shaft-section, slip-clutch members secured on the respective rotary shaft-sections and yieldingly connecting them whereby the second shaft-
10 section is driven by the first, a spring device normally restraining the longitudinal movement of the first shaft-section, a ratchet-wheel upon said second shaft-section, a pawl adapted to engage said ratchet-wheel, and a sheet-actuated tripping device controlling said pawl.

17. The combination of a support for a pile of sheets, with a sheet-moving instrument, means for elevating the sheet-moving instrument, and means controlling the operation of the instrument-elevating means including a shaft-section which is movable about its axis, a toothed member moved by and adapted to control the movement of said shaft-section, a pawl adapted to engage the said toothed member to arrest its movement, and a trip-finger in the path of the sheets suitably connected with and controlling the operation of said pawl.

40 18. The combination of a support for a pile of sheets, with a sheet-moving instrument, means for elevating the sheet-moving instrument, and means controlling the operation of the instrument-elevating means including a shaft-section which is movable about its axis, a toothed member moved by and adapted to control the movement of said shaft-section, a pawl adapted to engage the said toothed member to arrest its movement, a trip-finger in the path of the sheets suitably connected with and controlling the operation of said pawl, and cam mechanism arranged to raise the trip-finger from the path of the sheets and disengage the pawl from the toothed member.

45 19. The combination of a support for a pile of sheets, with a sheet-moving instrument, means for elevating the sheet-moving instrument, and means controlling the operation of the instrument-elevating means including a rotary shaft-section carrying a ratchet-wheel, a pawl to engage said ratchet-wheel, a trip-finger suitably connected with and controlling the operation of said pawl,

5 and cam mechanism arranged to elevate the trip-finger from the path of sheets and disengage the pawl from the ratchet-wheel.

20. The combination of a support for a pile of sheets, with a sheet-moving instrument, means for elevating the sheet-moving instrument, and means controlling the operation of the instrument-elevating means including a rotary shaft-section, a toothed or ratchet member moved by and controlling the rotation of said shaft-section, a pawl to engage said ratchet member, a trip-finger suitably connected with and controlling the operation of said pawl, a longitudinally-movable rotary shaft-section, a slip-clutch connecting the shaft-sections, and cam mechanism arranged to elevate the trip-finger from the pile of sheets and disengage the pawl from the ratchet member.

21. In a mechanism of the class described, the combination of a sheet-moving instrument, controlling mechanism therefor, including a shaft which is movable about its axis, a toothed member adapted to arrest the movement of said shaft, a pawl supported in operative relation to the toothed member, a trip-finger supported in the path of sheets and suitably connected to the pawl, a rock-arm connected with the trip-finger and pawl, and a cam arranged to operate said rock-arm.

22. In a mechanism of the class described, the combination of a sheet-moving instrument, a controlling mechanism therefor including a rotary shaft-section carrying a ratchet-wheel, a pawl supported in operative relation to the ratchet-wheel, a trip-finger pivoted independently of the pawl and supported in the path of sheets a link connecting the trip-finger and pawl, a rock-arm suitably connected with the trip-finger and pawl, and a rotary cam adapted to operate said rock-arm.

23. The combination, in a machine of the class described, of a sheet-moving instrument, a controlling mechanism therefor including a rotary shaft-section carrying a ratchet-wheel, a pawl supported in operative relation to the ratchet-wheel, a rock-arm adapted to engage the pawl for releasing its engagement upon the ratchet-wheel, a cam actuating said rock-arm, a second rock-arm suitably connected with the first rock-arm, a trip-finger journaled upon the second rock-arm, and a link connecting said trip-finger and pawl.

24. In a machine of the class described, the combination of a support for a pile of sheets, a rotary shaft, a sleeve journaled upon said shaft, a rock-arm journaled upon said sleeve, a rotary sheet-moving instrument mounted upon said rock-arm, gearing between said sheet-moving instrument and said shaft, means of engagement between said sleeve and said rock-arm for controlling

the position of the sheet-moving instrument, spring mechanism connected with said sleeve for elevating the sheet-moving instrument, sheet-actuated tripping mechanism controlling the action of the spring mechanism, and cam mechanism suitably connected with said sleeve for resetting the spring mechanism and allowing the sheet-moving instrument to move into engagement with the pile.

25. In a machine of the class described, the combination of a support for a pile of sheets, a rotary shaft, a sleeve journaled upon said shaft, a rock-arm journaled upon said sleeve, a rotary sheet-moving instrument journaled upon said rock-arm, gearing between said sheet-moving instrument and said shaft, means of engagement between said sleeve and said rock-arm, a longitudinally-movable shaft-section means for moving said shaft-section about its axis, a spring mechanism connected with said sleeve for elevating the sheet-moving instrument, means controlled by the longitudinal movement of said shaft-section for releasing the spring mechanism, sheet-actuated tripping mechanism controlling the longitudinal movement of said shaft-section, and cam mechanism suitably connected with said sleeve for resetting the spring mechanism

and allowing the sheet-moving instrument to move into engagement with the pile.

26. In a machine of the class described, the combination of a support for a pile of sheets, a rotary shaft, a sleeve journaled upon said shaft, a rock-arm journaled upon said sleeve, a rotary sheet-moving instrument journaled upon said rock-arm, gearing between said sheet-moving instrument and said shaft, means of engagement between said sleeve and said rock-arm, a longitudinally-movable rotary shaft-section driven from said shaft, a spring mechanism connected with said sleeve for elevating the sheet-moving instrument, a latching device controlled by the longitudinal movement of said shaft-section, for normally restraining the spring mechanism, sheet-actuated tripping mechanism controlling the longitudinal movement of said shaft-section, and cam mechanism suitably connected with said sleeve for compressing the spring mechanism and allowing the sheet-moving instrument to move into engagement with the pile.

TALBOT C. DEXTER.
